UNITED STATES PATENT OFFICE

HARRY FRIELAND, OF NEWARK, NEW JERSEY

BRASSIÈRE

Application filed July 30, 1930. Serial No. 471,798.

This invention relates to apparel and more particularly to an undergarment known as a brassière, corset, combinations, foundation garment, and the like.

5 One object of the invention is to provide a brassière, corset, combination, foundation garment and the like, having an improved construction whereby it will fit very comfortably and firmly support the breasts.

10 Another object of the invention is to provide the brassière, corset, combination, foundation garment and the like, with breast receiving pockets which will receive and support the breasts without causing pressure 15 which is liable to cut off circulation and cause injury to the breasts.

Another object of the invention is to provide the pockets with front and rear wall members secured about marginal portions

20 of openings in the body portion of the brassière and so shaped that when the breasts are engaged in the pockets they will be well supported and prevented from moving.

Another object of the invention is to so 25 form the walls of the pockets that they will not only conform to the shape of the breasts but also conform to the size thereof.

The invention is illustrated in the accompanying drawings wherein:

30 Figure 1 is a front elevation of the improved brassière or like garment.

Figure 2 is a rear elevation thereof.

Figure 3 is a view of the blank from which the body portion of the brassière or like 35 garment is formed.

Figure 4 is a section taken along the line 4—4 of Figure 1.

Figure 5 is a fragmentary section taken along the line 5—5 of Figure 1, and

40 Figure 6 is a view of the blank from which the outer wall of the pocket is formed.

In describing the invention I shall refer to the drawings in which similar reference characters designate corresponding parts 45 throughout the several views.

The body portion 1 of the improved brassière is formed from a fabric blank having the outline shown in Figure 3 and it is to be understood that end portions 2 will be 50 of such length that they may be extended and have their lower portions well supported.

rearwardly about the body and secured together in any desired manner. Openings 3 are formed in the body and between these openings the body is cut from its upper edges to form a slot 4 which extends the major 55 portion of the depth of the body but terminates in spaced relation to its lower edge. Elastic webs 5 are secured against the body in bridging relation to the slot 4 to exert pulling action when the brassière is worn. In 60 order to brace the body beneath the slot there is provided a reinforcement 6 consisting of a rectangular piece of fabric folded diagonally to form triangular portions 7 which are secured against front and rear faces of the 65 body with their upper ends overlapping the lower ends of the elastic strips 5. This greatly strengthens the garment and prevents danger of it tearing.

Each of the breast receiving pockets has 70 an outer or front wall 8 and an inner or rear wall 9. The front wall is conical in shape and is formed from a substantially circular blank 10 having a segment 11 cut therefrom. 75 By this arrangement portions of the blank at opposite sides can be overlapped as shown at 12 thereby causing the blank to assume the conical shape desired and also permitting dimensions thereof to be controlled when shaping the wall. After the wall has been 80 shaped it is set in place and its marginal portions sewed to the body about the openings.

The inner wall is crescent shaped and consists of a blank cut intermediate its ends from its upper edge similar to the manner in which the blank for the outer wall is cut. 85 This blank has portions at opposite sides of the cut overlapped as shown at 13 and the upper edge portion of the inner wall is rolled as shown at 14. By this arrangement the inner walls when secured about the lower portions of the openings will assume the position shown in Figure 4 and since the walls extend from the openings in opposite directions the pockets will be so shaped that the 90

breasts will be snugly received in the pockets and held firmly in position. The fact that the pockets have the shape shown in Figure 4 permits the breast to fit into the pockets 100 and have their lower portions well supported.

The taper of the front walls causes the pockets to fit properly about the breasts and allows the brassière to be tightened at the back without danger of the breasts being injured by excessive compression. The rolled edge of the rear wall prevents a rough edge and causes the brassière to be very comfortable when worn.

From the foregoing description of the construction of my improved undergarment, it will be seen that I have provided a simple, inexpensive and efficient means for carrying out the objects of my invention and while I have particularly described the elements best adapted to perform the functions set forth it is obvious that various changes in form, proportion and in the minor details of construction may be resorted to without departing from the spirit or sacrificing any of the principles of the invention.

Having thus described the invention what is claimed is:

A garment comprising a body formed with apertures spaced from each other longitudinally of the body, pockets secured about marginal portions of the apertures and projecting forwardly from the body, said body being split vertically from its upper edge between said apertures, an elastic web bridging the split and secured to the body and adapted to exert pulling action upon the body and hold the garment snugly in place when worn, and a reinforcing sheet straddling the lower edge of said body and having portions extending upwardly therefrom and secured against front and rear faces of the body and overlapping the lower end portion of the elastic web.

In testimony whereof I affix my signature.

40 HARRY FRIELAND.
